UNITED STATES PATENT OFFICE.

PETER HLEB, OF ELIZABETH, NEW JERSEY, ASSIGNOR TO THE SINGER MANUFACTURING COMPANY, OF ELIZABETH, NEW JERSEY, A CORPORATION OF NEW JERSEY.

FEEDING MECHANISM FOR SEWING MACHINES.

Application filed November 5, 1920. Serial No. 421,815.

To all whom it may concern:

Be it known that I, PETER HLEB, a citizen of the United States, residing at Elizabeth, in the county of Union and State of New Jersey, have invented certain new and useful Improvements in Feeding Mechanisms for Sewing Machines, of which the following is a specification, reference being had therein to the accompanying drawings.

10 This invention relates to sewing machine feeding mechanism, more particularly of the reversible type such as disclosed in the United States patent to Diehl No. 575,339. In the construction disclosed in the Diehl 15 patent, the feed-regulating lever is formed with an obtuse V-shaped recess to receive the tapered end of an adjusting screw which serves as an abutment to limit the movements of the feed-reversing lever in opposite 20 directions. A disadvantage of this prior construction lies in the non-indicating character of the adjustment. A predetermined stitch length cannot be secured except by turning the adjusting screw to what is 25 thought to be about the right position and subsequently testing the result by trial sewing, repeating this "cut-and-try" process, until the desired stitch length is secured. Another disadvantage of said prior 30 construction lies in the inherent sensitiveness of the feed-adjustment. There is a tendency for the faces of the V-shaped recess and the point of the adjusting screw to become worn irregularly and when these parts begin to 35 wear it becomes increasingly difficult to accurately secure a desired feed adjustment. The effect of this condition is aggravated by the relative nearness of the adjusting screw to the pivot of the feed-adjusting lever and 40 by the tendency of the side thrust on the feed-adjusting lever to wear the pivotal support therefor and permit side play.

The present invention has for an object to 45 provide a feed adjustment and stop expedient of the type disclosed in said Diehl patent which will be simple in construction and inexpensive to manufacture and which will be accurate and reliable in use. Another object of the invention is to provide 50 a stop expedient of the class described which will be self-indicating in character,

thus enabling the operator to select and accurately obtain at an instant's notice, the desired feed adjustment.

In accordance with the present improvement, the adjustable abutment or stop-element for the feed-regulating lever is provided with a plurality of fixedly related stops which are in plain sight. This element is adjustable so that any selected one 55 of said stops may be shifted into operative relation with the feed-regulating lever. Preferably, the frame of the machine is formed with a circular depression in which is seated a circularly adjustable apertured 60 plate through which the free end of the feed-regulating lever extends. In the present embodiment of the invention the feed is of the reversible type and the stop-plate is preferably so located that when the 65 feed-adjusting lever is in neutral position, i. e., the position of zero feed, it occupies a position at the center of the stop-plate and may be shifted vertically in opposite directions away from said center to increase the 70 amplitude of feed in both a forward and a reverse direction. The aperture in the stop-plate may comprise a merged series of angularly spaced diametrical slots of different 75 lengths intersecting at the center of adjustment of the stop-plate. Preferably, the 80 slots are of progressively greater lengths and each extends equal distances on opposite sides of the center of adjustment, so that whichever slot or corresponding pair of 85 stops is selected and shifted into register with the path of movement of the feed-regulating lever, the ends of the selected slot which constitute the corresponding pair 90 will serve to arrest the feed-regulating lever 95 at opposed positions of equal feed length.

In the accompanying drawings which illustrate the invention in its preferred embodiment in a machine such as represented in the Miller et al. Patent No. 229,629, of 25 July 6, 1880, Fig. 1 is a fragmentary front side elevation of the bracket-arm or goose-neck of a sewing machine embodying the invention. Fig. 2 is a vertical section of the complete sewing head on the line 2—2, Fig. 100 1. Fig. 3 is a detail perspective view of the stop-plate and associated parts and Fig. 4

is a diagrammatic view illustrating the intersecting arrangement of the elemental diametrical slots which are merged together to form the irregular aperture in the stop-plate.

The frame of the machine comprises the usual bed A and bracket-arm or goose-neck B within which is housed the main-shaft C formed with the crank D which operates, as usual through the pitman 5 and rock-lever 6 to oscillate the shuttle-driving shaft 7. The main-shaft C carries the cam 8 which is embraced by the forked upper extremity of the usual feed-actuating pitman 9 connected at its lower end to an arm 10 fixed to the feed-advancing rock-shaft 11. The rock-shaft 11 also has fixed thereto the rock-arm 12 to which is pivoted at 13 the feed-bar 14 carrying the feed-dog 15 and resting upon the feed-lifting cam 16 fixed to the shuttle-driving shaft 7. The feed-actuating pitman 9 is connected by the link 17 to one arm of the bellcrank feed-regulating lever 18 which is pivoted at 19 to a lug 20 projecting inwardly from the bracket-arm B.

The bracket-arm B is preferably formed at its front side with a circular depression or recess 21 diametrically of which extends the vertical slot 22 in the front wall 20 of the bracket-arm. The slot 22 admits the shank of the extension handle 23 which is screwed into the other arm of the feed-regulating lever 18. When the handle 23 is horizontal or midway between the ends of the slot 22 it is in so-called neutral position or the position of zero feed. When it is shifted upwardly a given distance, the feed is forward or toward the right, Fig. 2, when shifted downwardly a similar distance, the amplitude of the feed is unchanged but the direction of feed is reversed.

Seated within the circular recess 21 is the circularly adjustable stop-plate 24 having a finger-piece 25 and a segmental slot 26 through which passes the holding screw 26'. The stop-plate 24 is formed with a merged series of angularly spaced diametrical slots 27 intersecting at the center 28 of adjustment as indicated in Fig. 4. These slots are of varying lengths and each extends equal distances on opposite sides of the center 28. The stop-plate 24 and associated stops are in plain sight and it will be evident that by shifting the plate 24 circularly any one of the slots may be set in register with the slot 22, whereby the ends of the selected one of said slots will act as abutments or stops 29 for the feed-regulating lever 18. As these stops 29 are arranged in pairs with the stops of each pair at equal distances from the center 28 or neutral position of the lever 18, it will be evident that the feed may be instantly reversed, as when finishing off a seam, without affecting the length of the stitch selected.

While disclosed in connection with a reverse feed mechanism, the invention is, in certain aspects, useful in machines not possessed of the feed-reversing feature, as well be apparent from the present disclosure to those skilled in the art.

Having thus set forth the nature of the invention, what I claim herein is—

1. The combination with sewing machine feeding mechanism including a shiftable feed-regulating element, of a member having a series of pairs of fixedly related stops, said member being shiftable to position any selected pair of said stops in the path of the feed-regulating element to arrest the latter at predetermined positions of adjustment. 75

2. The combination with sewing machine feeding mechanism including a shiftable feed-regulating element, of a stop-plate cut away to form a plurality of fixedly related 85 stops and adjustable so that any selected one of said stops may be shifted into operative relation with the feed-regulating lever.

3. The combination with sewing machine feeding mechanism including a shiftable 90 feed-regulating element, of a circularly adjustable member having a series of angularly spaced stops disposed at different distances from the center of adjustment of said member and adapted to locate the feed-regulating element at various predetermined positions of adjustment. 95

4. The combination with sewing machine feeding mechanism including a shiftable feed-regulating lever, of a circularly adjustable apertured stop-plate through which said lever projects, the aperture in said plate comprising a series of radial slots of different lengths. 100

5. In a sewing machine, the combination 105 with reversible feeding mechanism including a feed-controlling element reversely shiftable through a neutral position, of a plurality of pairs of connected stops for said element, the stops of each pair being arranged, respectively, at opposite sides of the neutral position of said element. 110

6. In a sewing machine, the combination 115 with feeding mechanism including a shiftable feed-controlling element, of a circularly adjustable apertured stop-element entered by said controlling element and formed with a series of stop-shoulders at varying distances from the center of adjustment.

7. In a sewing machine, the combination 120 with reversible feeding mechanism including a reversely shiftable feed-controlling element, of a circularly adjustable apertured stop-element entered by said controlling element and formed with a plurality of pairs 125 of diametrically opposed stop-shoulders at varying distances from the center of adjustment.

8. The combination with a reversible feeding mechanism including a feed-con- 130

trolling element shiftable in opposite directions from a neutral position, of a circularly adjustable apertured stop-plate through which said feed-controlling element projects 5 said stop-plate having wall portions spaced from the neutral position of the feed-con-

trolling element, certain of said wall por-

tions being spaced greater distances from said neutral position than others of said wall portions.

In testimony whereof I have signed my name to this specification. 10

PETER HLEB.
